ATTORNEY

UNITED STATES PATENT OFFICE.

WILLIAM CROMWELL KNOX, OF NEW YORK, N. Y.

STATION-INDICATOR.

1,336,035.

Specification of Letters Patent.

Patented Apr. 6, 1920.

Application filed December 9, 1918. Serial No. 265,822.

To all whom it may concern:

Be it known that I, WILLIAM CROMWELL KNOX, a subject of the King of England, residing in the city of New York, borough 5 and county of Bronx, in the State of New York, have invented a certain new and useful Improvement in Station-Indicators, of which the following is a specification.

The invention relates to devices mounted 10 in railway cars to indicate the next station-stop, and is designed more particularly for service in subways and analogous transportation lines.

The object of the invention is to provide a 15 device of this character, easily installed and so located in the car as to be easily read from all parts thereof, and which shall be simple and economical in construction and easily operated, and perform its function 20 efficiently.

The invention consists in certain novel 25 features and details of construction and arrangement by which the above objects are attained, to be hereinafter described and claimed.

The accompanying drawings form a part 30 of this specification and show an approved form of the invention.

Figure 1 is a transverse section of a car body equipped with the improved indicator, the latter being shown in side elevation.

Fig. 2 is a partial side view and vertical longitudinal section, on a larger scale, showing the indicator alone.

Fig. 3 is a transverse vertical section 35 through the indicator alone, corresponding to Fig. 1.

Fig. 4 is a horizontal section, partly in plan view, showing certain details on a still 40 larger scale.

Fig. 5 is an elevation showing the contact points of an electric switch by which the names of the stations on the indicator are illuminated.

Similar letters of reference indicate the 45 same parts in all the figures.

A is the body of car having a longitudinally extended elevated portion of the roof A¹, providing the usual ventilator space. 50 The indicator is mounted in such space, transversely of the car, preferably about midway between the ends of the latter so as to be plainly visible from all parts of the car.

The indicator comprises a light rectangular case B preferably of sheet metal, di-

vided by a series of horizontal partitions B¹ and vertical partitions B² into a number of rectangular cells or compartments open at the ends, or sides of the case and each 60 containing an incandescent lamp C.

The compartments are arranged to form a plurality of vertical series located side by side and all are covered on each open face by a sheet or plate D of thin metal or other 65 suitable material having the names of the stations cut therein to match to the compartments so as to be illuminated by the lamps.

The sheets D are preferably mounted each 70 in a frame D¹ adapted to slide vertically in ways A² formed on the ends of the case A on each face, and are held in place by bolts E extending through the lower portions of the frames and through the case in the lower 75 row of compartments, and supported by the floor or bottom of the case.

A translucent lining F of suitable fabric or other material covers the inner face of each sheet D, extending across the openings 80 therein forming the station-names, and showing the latter in strong contrast with the opaque body of the sheet.

The lamps are connected by suitable wiring, not shown, to contact points G¹ arranged circularly on the rear face of a switchboard G in the path of a switch-arm G² mounted on a shaft G³ and moved by a handle G⁴ on a pointer G⁵ on the front face of the switchboard to cause any selected 90 lamp to glow as indicated by the pointer relatively to a circle of points G⁶ on such front serving to aid in such selection. The contact points are separated by insulation, and a long strip of insulation G⁷ is provided 95 to present an interval on which the switch-arm G² rests when the indicator is out of use, as at the end of a trip.

In starting from the terminal station, the guard or attendant moves the pointer G⁵ to 100 the first point G⁶ which action correspondingly moves the switch-arm G² to the first contact point in the series G¹ on the rear of the switchboard and thus completes the circuit through the first lamp of the series and 105 illuminates the first station name. On leaving that station he moves the pointer to the next in the series and illuminates the second station name, and so on successively if the train is a local making all the stops. If 110 stops are to be made at express stations only, the guard moves the pointer to illuminate

the name of the next express-stop, momentarily illuminating the local stations between as the pointer is swung over them. If the guard swings the pointer to the wrong name he simply swings it backward or forward to the correct name.

As the material of the lining F is lighter than the painted surface of the opaque sheet D the names of all the stations may be read 10 by the reflected light from the car lamps, while the next station-stop is brilliantly illuminated by transmitted light from the lamp C in that compartment, thus enabling the passenger readily to follow the succession 15 of names and be prepared to leave the car when his station is reached. Express stations may be specially marked by a cross, star or other distinguishing sign on the indicator, so that the passenger can readily 20 find the station at which to change to a local or express train in reaching his destination.

By locating the indicator in the ventilator space in the roof of the car, it is out of the way and at the same time conspicuously 25 placed and plainly visible from all parts of the car and not concealed by standing passengers. The switchboard may be located at any point conveniently accessible to the guard or attendant.

30 If the route is to be changed it is only necessary to remove the bolts E and plates D with their frames D¹, and substitute other

plates and frames similarly spaced but bearing the station-names for the new route.

The indicator may be supported in the 35 ventilator space by any suitable means. It is shown as suspended from the roof by bolts H.

The apparatus and its operation are eminently simple and completely under the control 40 of the attendant whose duty is simply to illuminate the name of the next station-stop immediately on leaving the preceding station.

I claim:—

In a station indicator, a case adapted to be suspended from the roof of a car at the midlength of the latter, horizontal and vertical partitions in said case dividing its interior into a plurality of compartments open 50 at each end, vertical ways on the sides of said case, plates removably received in said ways and covering such sides, having station-names cut therein to match to such compartments, a translucent lining covering the inner face of each of said plates, an incandescent electric lamp in each compartment, and a switch adapted to control said lamps and illuminate such compartments and station-names successively. 55

60 In testimony that I claim the invention above set forth I affix my signature.

WILLIAM CROMWELL KNOX.
